(57) **CLAIM**

We claim the ornamental design for a shower dispenser, as shown and described.

DESCRIPTION

FIG. 1 is an elevation view showing the front portion of the shower dispenser of the present invention;

FIG. 2 is an elevation view showing the back portion thereof;

FIG. 3 is an elevation view showing the right side thereof; FIG. 4 is an elevation view showing the left side thereof;

FIG. 5 is a top view thereof;

FIG. 6 is a bottom view thereof; and,

FIG. 7 is an isometric view thereof.

The portions shown in dashed lines in the figures are included for illustrative purposes only and form no part of the subject design.
